UNITED STATES PATENT OFFICE.

MOSES MOSLER, OF NEW YORK, N. Y., AND CARL BARTELS, OF HAMILTON, OHIO,
ASSIGNORS TO THE MOSLER SAFE COMPANY, OF NEW YORK, N. Y.

SAFE.

Application filed October 17, 1919. Serial No. 331,331.

To all whom it may concern:

Be it known that we, MOSES MOSLER and CARL BARTELS, citizens of the United States, residing at New York, New York County, 5 New York, and Hamilton, Butler County, Ohio, respectively, have invented certain new and useful Improvements in Safes, of which the following is a specification.

This invention, pertaining to fireproof 10 safes or fireproof cabinets, will be readily understood from the following description taken in connection with the accompanying drawing in which:—

Fig. 1 is a front elevation of a safe embodying our improvements;

Fig. 2 a horizontal section through a portion of the safe in the plane of line *a* of Fig. 1.

Fig. 3 a prospective view of one of the 20 corners of the safe when the jamb, instead of being mitered, is formed with a filling piece provided with a doweling socket:—

Fig. 4 a diagram of the outer sheet of the 25 body, before bending.

In the drawing:—

1, indicates the body of the safe:

2, the door of the safe:

3, the metallic external shell of the safe, 30 comprising the sides, top and bottom:

4, the door-jamb:

5, an inturned rear flange of the shell:

6, the back-plate of the shell, secured to the flange 5:

7, the interior box of the safe, this box 35 being open at its front and having its front edges secured to the rear edges of the door-jamb:

8, a metallic lining for the shell:

9, a layer of insulating non-combustible 40 material, as asbestos paper, interposed between the shell and the lining:

10, the front of the door:

11, the margin of the door:

45 12, an inturned flange on the back of the door margin:

13, the metallic back-plate of the door:

14, a metallic lining for the front and margin of the door:

15, an insulating non-conducting material 50 interposed between the lining 14 and the metal of the door:

16, the exterior front of the safe, surrounding the door-jamb:

17, a filling-piece illustrating a substitution for the mitering of the door-jamb:

18, a socket formed in the front exterior of the filling-piece:

19, a filling-piece at the corner of the door to co-operate with the filling-piece 17:

20, a dowel projecting from filling-piece 19 and adapted to co-operate with socket 18 in the filling-piece of the door-jamb:

21, appropriately formed notches in the sheet of which the exterior shell of the safe 65 is formed when the margins are mitered: and

22, a square notch formed in the sheet from which the shell is bent, such notches to be provided in case the front corners of 70 the safe body are to be provided with such filling-pieces as are illustrated in Fig. 3:

The shell of the safe, together with the front 16 and the jamb-portion 4 and the flange 5 is, preferably, formed of one piece 75 of metal bent to shape, the metal being first cut to proper form, as illustrated in Fig. 4, and then bent, a seam being formed, by welding, at one of the lower corners of the safe. If the corners of the body are to be mitered, then the sheet will be cut

with appropriate notches 21, while if the corners of the jamb are to be provided with sockets, as illustrated in Fig. 3, then the sheet may be provided with notches as 80

22 in Fig. 4, to receive the filling-pieces 85 to which the appropriate edges of the sheet forming the safe-body are united by welding.

These filling pieces may be metallic 90 castings or stampings, and the welded junctions are preferably to be made by autogenous welding process. It is preferable

that the filling pieces 17 should be arranged to lie inside of and over lap the metal of the door-jamb, as illustrated in Fig. 3. The door 2 is preferably constructed with its front and margins formed of a single sheet bent up to shape, the margin having welded corners. If the door-jamb is provided with sockets, then the corners of the door, instead of being formed for mitering, and mitered, are formed to receive the filling-pieces 19 which carry the dowels 20, and in case the socketed filling-pieces 17 of the door-jamb interiorly over lap the door-jamb of the body sheet, then the margins of the door should appropriately over-lap the filling-pieces 19.

The interposed layer 9 of insulating material, and the metallic lining sheet are preferably laid against the metal of the shell before it is completely bent, so that the bending of the three layers may take place at once, and the same remarks apply to the construction of the door. Regardless of whether the lining and insulating material be bent at one time with the shell or door, the character of the bends serves to prevent any displacement of the layer of insulation. The back-plate 6 may be secured to the flange 5, as by screws, and is to be formed of two thicknesses of metal with an interposed layer of insulating material. The space between the shell and the interior box 7 may, if desired, be filled with any suitable non-conducting material, and the same remarks apply to the door, whose jamb-joint is preferably stepped, as illustrated.

The lining, conforming closely to the shape of the shell and of the door, serves in maintaining the interposed layer of insulating material in place, regardless of the presence of other filling.

We claim:—

1. A safe comprising a metallic shell and a layer of non-combustible material disposed against the interior of said shell, said shell and layer extending in parallel relation throughout an exterior portion of the safe, a front portion, and a stepped door jamb spaced from the said exterior portion.

2. A safe comprising a metallic shell and lining and a layer of non-combustible material interposed between said shell and lining, all three members extending in parallel relation throughout an exterior portion of the safe, a front portion, and a stepped door jamb spaced from the said exterior portion.

3. A safe comprising outer and inner metallic sheets with an interposed non-combustible layer, all three members being bent to form outer and inner spaced wall portions and a portion connecting the same, said inner wall portion forming a stepped door jamb and having said three members bent to extend in parallel relation throughout the various steps thereof.

4. A safe comprising outer and inner metallic sheets with an interposed non-combustible layer, all three members being bent to form a side wall with offsets therein, a front wall and a stepped door jamb spaced inwardly from said side wall, said three members extending in parallel relation throughout said portions of the safe.

5. A safe comprising a metallic shell and a non-combustible layer disposed against the inner face thereof, said members being bent to extend in parallel relation throughout the sides, top, bottom, front, stepped door jamb spaced inwardly from the exterior portions, and inturned rear marginal flange, a back plate secured to said flange and an interior box having its front edges secured to the rear edges of the door jamb and its rear portion spaced from said back plate.

6. A safe comprising a metallic shell and lining and a layer of non-combustible material interposed between said shell and lining, all three members extending in parallel relation throughout the sides, top, bottom, front, stepped door jamb spaced inwardly from the exterior portions, and inturned rear marginal flange, a back plate, comprising metallic inner and outer members with interposed non-combustible layer, secured to said flange, and an interior box having its front edges secured to the rear edges of the door jamb and its rear portion spaced from said back plate.

7. In safe construction, a door having a front and a stepped margin, and including a metallic shell and a layer of non-combustible material disposed against the inner face thereof, both bent to extend coextensively in parallel relation throughout said front and stepped margin of the door.

8. In safe construction, a door having a front and a stepped margin, and including a metallic shell and lining and an interposed non-combustible layer, all three being bent to extend coextensively in parallel relation throughout the front and stepped margin of the door.

9. A safe comprising a door having a metallic shell and lining and an interposed non-combustible layer, all three being bent to extend in parallel relation throughout the front and stepped edge portions of the door, said shell having a marginal flange at the rear, and a back plate secured to said flange and spaced from the front portion of the door.

10. A safe comprising a stepped door jamb formed of bent up sheet metal provided with corner gaps, and stepped filling pieces disposed in said gaps, welded in place, and provided with sockets in their front surfaces.

11. A safe comprising a stepped door jamb formed of bent up sheet metal provided

with corner gaps, and stepped filling pieces disposed in said gaps, welded in place, and provided with sockets in their front surfaces, and a door having its margin formed 5 of bent-up sheet metal, with stepped filling pieces forming corner junctures for the door margin and dowels carried by said filling pieces and adapted to co-operate with said sockets, said jamb filling pieces lying inside 10 of and overlapping the metal of the jamb, and said door filling pieces being correspond-

ingly overlapped by the metal forming the door margin.
